UNITED STATES PATENT OFFICE

138,630

DESIGN FOR A DRINKING GLASS OR THE LIKE

Alfred J. F. Erbe, Weston, W. Va.

Application May 18, 1944, Serial No. 113,674

Term of patent 7 years

(Cl. D36—8)

To all whom it may concern:

Be it known that I, Alfred J. F. Erbe, a citizen of the United States, residing at Weston, in the county of Lewis and State of West Virginia, have invented a new, original, and ornamental Design for a Drinking Glass or the like, of which the following is a specification, reference being had to the accompanying drawing, forming part thereof.

I claim:

The ornamental design for a drinking glass or the like, as shown.

ALFRED J. F. ERBE.
